UNITED STATES PATENT OFFICE.

ANNA HEDDA ADELAIDE DE MECKLEMBOURG, OF PARIS, FRANCE.

FOLDING AND PORTABLE NIGHT-STOOL.

1,236,407.

Specification of Letters Patent. Patented Aug. 14, 1917.

Application filed November 4, 1913. Serial No. 799,127.

To all whom it may concern:

Be it known that I, Baronne ANNA HEDDA ADELAIDE DE MECKLEMBOURG, of 119-121 Avenue des Champs-Elysées, in the city of 5 Paris, Republic of France, have invented a Folding and Portable Night-Stool, of which the following is a full, clear, and exact description.

The invention relates to a portable and 10 folding night commode which can be carried conveniently in the hand, in the same way as a suit case or traveling bag. The night commode is specially intended for motorists and travelers who do not wish to make use 15 of the conveniences provided in railway carriages and hotels; it is however also very serviceable in hospitals.

The new device consists in the special 20 combination of a seat mounted on removable or folding feet with a collapsible pan, the combination being such that the whole arrangement can be easily folded and inclosed in a cover or casing. It then takes up only 25 a very small amount of room, and can be conveyed in a convenient manner like a suit case or other baggage. A special feature 30 of the arrangement is that the telescopic pan occupies a definite and secure position, both when ready for use and also when all the 35 parts are folded up.

The invention is illustrated in the drawing, Figure 1 being a vertical section through the whole appliance as ready for use, Fig. 2 a vertical section through the 35 pan only; Fig. 3 a partial view from above, Figs. 4 and 5 separate views of the joints between the frame, seat and pan.

As can be seen from the drawing the night commode consists of a seat *a* which 40 may be of any external shape for instance square, and is provided with an opening adapted to be closed by a lid. The seat is preferably made of wood but it may also be of any other material which forms a 45 suitable substitute for wood and will make a seat that is equally light and strong.

The seat *a* rests on a frame *d* supported by legs *e*. These legs may be permanently attached to the frame, or be detached or 50 folded on same, according as circumstances may require. In the form illustrated the feet are attached to the frame by hinges *o* and are held in their vertical position by detachable struts *p*. The frame *d* is provided in the middle with a circular open-

ing which serves for the reception of a pan *f*. The pan is provided with a flanged rim *g*, which rests on the frame and is held in position by the seat *a* being turned down over it.

The pan *f* is in the shape of a truncated cone and is composed of two annular sections *h*, *i* which fit into one another in the known telescopic manner. When drawn out, the walls of the two sections fit each 65 other closely, and the whole forms a perfectly stanch receptacle, which is secured in position for use, by means of struts *h'*, the hooked ends of which are inserted into eyes provided underneath the bottom of the 70 pan. The collapsing of the pan is effected by pushing the sections into one another as shown in Fig. 2, in which position the two parts are held together by means of short hooks *i'*. The pan is provided with a lid *k* 75 and both pan and lid may be made of aluminium in order to keep the weight down as low as possible.

For conveyance, the struts which spread the legs are dismounted, the legs *e* are then 80 folded up, and the pan is telescoped and secured. The legs can then be secured on the underside of the device by means of straps or other suitable means. The struts *p* will lie against the bottom of the pan. In 85 order to make the lid *k* fit tightly and prevent rattling, the external lid *b* which closes the whole, is provided with a pad *b'* of rubber or the like, which presses the lid *k* down when the lid *b* is fastened down by 90 means of a hasp *b²* to a catch *d'* on the same frame *d*. The seat *a* and the lid *b* are adapted to pivot on the same hinges *d²* of the frame *d*, the lid *b* being held by the curved hinge members *d³* (Figs. 4, 5). This 95 not only simplifies the connecting together of the parts, but is also more convenient inasmuch as the lid *b* is turned right out of the way when the commode is to be used.

The folding night commode as described 100 can be inclosed as a whole in a cover or casing of suitable shape and provided with handles for transport.

When the device is desired to be used, the legs *e* are first set up, fastened together by 105 means of the struts *p* and the lid *b* is lifted. To expand the pan and draw the parts firmly together, the bottom *i* is provided on the underside with a handle *h²*. This enables the parts to be brought into such 110

a position that they can be locked together by means of the struts h' and without having to touch the inside of the pan.

The bottom of the pan is preferably provided with four equal eyes for the hooks of the struts h' so that the pan will stand level on the ground. The hooks can be inserted in either pair of eyes, as convenient. With the same object in view the handle h^2 is recessed in the underside of the bottom i .

Claims:

1. A folding and portable commode comprising a frame, folding legs for supporting said frame, a collapsible pan, a cover therefor, a seat hinged upon said frame and arranged to secure said pan thereon, means for rigidly maintaining said pan in its open condition and in its collapsed condition, a movable member carried by said frame and adapted to extend over said pan, a resilient pad on said member adapted to engage and lock the cover of said pan and means adapted to clamp the collapsed pan against vibration when the legs are folded.

2. A folding and portable commode comprising a frame, folding legs for supporting said frame, a collapsible pan provided in its bottom face with an external recess, a handle for said pan located in said recess, a cover for said pan, a seat hinged upon said frame and arranged to secure said pan thereon, means for rigidly maintaining said pan in its open condition and in its collapsed condition, a movable member carried by said frame and adapted to extend over said pan, a resilient pad on said member adapted to engage and lock the cover of said pan and means adapted to clamp the collapsed pan against vibration when the legs are folded.

3. A folding and portable commode comprising a frame, folding legs for supporting said frame, a collapsible pan provided in its bottom face with an external recess, a handle for said pan located in said recess, a cover for said pan, a seat hinged upon said frame and arranged to secure said pan thereon, means for rigidly maintaining said pan in its open condition and in its collapsed condition, a movable member adapted to ex-

tend over said pan, hinge members connecting said movable member with the hinges of the seat whereby said movable member and said seat are movable about the same pivots, a resilient pad on said movable member adapted to engage and lock the cover of said pan and means adapted to clamp the collapsed pan against vibration when the legs are folded.

4. A folding and portable commode comprising a frame, folding legs for supporting said frame, cross-bars connecting said legs in pairs, a collapsible pan comprising two telescopic sections the lower section being provided in its bottom face with an external recess, a handle for said pan located in said recess, ears carried by said lower section, members carried by the upper section of said pan and terminating in hooks adapted to engage said ears whereby the pan is rigidly maintained in open condition, hooks carried by said upper section and adapted to fit beneath the bottom of the lower section whereby said pan is maintained in collapsed condition, a cover for said pan, a seat hinged upon said frame and adapted to secure the pan thereon, a movable member carried by said frame and adapted to extend over said pan, hinge members connecting said movable member with the hinges of the seat whereby the movable member and said seat are movable about the same pivots, a resilient pad on said movable member arranged to engage and lock the cover of said pan, and a strut movably carried by one of said cross-bars and arranged to be detachably connected with the other cross-bar whereby said legs are secured in their upright, unfolded condition, said strut being further arranged to clamp the collapsed pan against vibration when the legs are folded.

The foregoing specification of my folding and portable night-stool signed by me this 23rd day of October 1913.

BARONNE ANNA HEDDA

ADELAIDE DE MECKLEMBOURG.
